FIRE EXTINGUISHER

Filed Aug. 19, 1929

UNITED STATES PATENT OFFICE

WALTER R. ROLLO, OF UTICA, NEW YORK, ASSIGNOR TO AMERICAN LA FRANCE AND FOAMITE CORPORATION, OF UTICA, NEW YORK, A CORPORATION OF DELAWARE

FIRE EXTINGUISHER

Application filed August 19, 1929. Serial No. 386,810.

The invention relates to the type of fire extinguisher which consists of a container having provision for holding liquid and dry ingredients unmixed, and which is set in action in time of fire by bringing the ingredients together to produce the extinguishing medium.

Its object is an extinguisher of this type, easily and inexpensively charged, and organized to ensure certainty and greater efficiency of operation, accomplished by the provision of means, herein exemplified in preferred form, whereby the dry or powder ingredient is protected against the action of the liquid while the extinguisher is idle and whereby in time of fire the entire body of powder is introduced into and thoroughly mixed with the liquid with a minimum of effort.

In the accompanying drawing, Fig. 1 shows the invention applied to a two and one-half gallon extinguisher of the so-called invertible type, Fig. 2 the application of the same form of the invention to an extinguisher of the non-invertible type and Fig. 3 a detail of the form shown in Fig. 1.

In Fig. 1 the extinguisher comprises a container 1 having a collar 2 at its upper end threaded to receive the closure cap 3 and having its bottom 4 spaced somewhat from the lower end of the container wall, as usual, to provide a skirt 5 on which the extinguisher stands. The collar is provided with an annular flange 6 which supports and to which is secured a sleeve 7, as by a similar flange 8 on the sleeve, the latter terminating short of the cap at its upper end and extending down into the container.

The space within the sleeve constitutes the powder compartment and although the particular ingredients are of no moment to the invention it is preferred that the dry element consists of a mixture of powdered soda, aluminum sulphate and licorice root such as is known to the trade, and which simply requires to be mixed with water to produce foam. It will be understood that all of the dry powders constituting the charge need not be mixed together although for simplicity of re-charging, as below described, it is pre-

ferred that they be so mixed and that the container hold water only. In any event it is important that the powder not only be kept out of direct contact with the liquid in the container until the extinguisher is to be used but also that it be sealed against vapor or moisture, which would bring about premature reaction of the ingredients and render them ineffective for use in time of fire. The powder may be variously protected and as may be best suited to the particular extinguisher but in the preferred form here shown the powder compartment is closed by a transverse plate or disc 9 which is secured to a plunger rod 10 and which is grooved, as indicated at 11, to receive the side walls of the compartment. The joint may be sealed by a gasket, or otherwise, so that when the plunger rod is in the position shown the powder compartment is closed against the entry of moisture, being sealed at its upper end by the container cap and flanges 6 and 8 and at its lower end by plate 9.

Rod 10 extends down to and through the bottom of the container, passing through a suitable gland 12 and serving to connect plate 9 with an external operating handle 13. The latter is protected by skirt 5 and being located approximately at the floor level is prevented from moving outwards and breaking the seal of the powder compartment so long as the extinguisher maintains its upright position. As a further precaution appropriate means may be provided, if desired, to lock the handle or plunger in this position; as shown in Figs. 1 and 3, the handle 13 may be mounted loosely on the plunger as a turn button, a strap 13a extending across the open end of the container bottom serving to hold the handle and plunger against outward movement and maintain the powder compartment hermetically sealed until the handle is turned and operated, as will be understood.

The lower end wall of the powder compartment, constituted by plate 9, is located above the liquid in the container, the latter being filled to the appropriate level through a filler opening, which is normally closed by a plug 14.

Rod 10 extends upwardly through the powder compartment and at its upper end, which is adjacent cap 3, carries an ejector member by which the powder is positively transferred from its compartment into the body of the container. The ejector may be variously constructed for this purpose but preferably consists of a plate 15 which constitutes an upper end wall for the powder compartment, although, as indicated, it is small enough to slide freely through the compartment when the plunger is operated.

Elbow 16 constitutes the outlet to the usual hose and nozzle 17 but when the extinguisher is charged for foam production the inner end of the elbow may be enclosed by a box 18 from which an outlet pipe 19 extends to the other end of the container, so that foam, which forms more readily in the upper part of the chamber, will be discharged and not the liquid itself.

To set the extinguisher in action, the container is inverted and the now exposed operating handle is released and pumped back and forth. The first stroke of the plunger breaks the hermetic seal and by means of plate 15 carries the mass of powder out of its compartment into the liquid and on succeeding strokes plates 9 and 15 operate to distribute the powder throughout the liquid, agitate the same and effect a thorough mixing of the ingredients.

It will be understood that the handle does not have to be pumped throughout the entire period of activity of the extinguisher, since its purpose is merely to release the dry ingredients from their sealed compartment and mix them with the liquid, the resulting extinguishing medium being expelled by the pressure of the gas generated by the reaction.

The extinguisher is recharged by returning the plunger to its initial position, to close the powder compartment, removing cap 3 and ejector plate 15 and introducing a fresh batch of powder, the liquid being added through the filler opening in the container wall.

Many of the parts already described will be recognized in the form of Fig. 2, in which the upper end of sleeve 20, which constitutes the powder compartment, is secured to the inside of the container cap and closed by it. As stated above, this extinguisher is designed for operation without inversion and accordingly the plunger rod extends upwardly through a gland in the cover instead of downwardly through the bottom of the container as in the previous form. As before, the rod carries plates 9 and 15 which respectively close the lower end of the compartment and eject the powder from it when the plunger is operated—in this case from an upper, extended position down into the container.

The action is in all respects similar to that already described.

In this case, the outlet elbow 16 may open directly through the container cap where it is always above the level of the liquid.

To permit access to the powder compartment for refilling the manner of securing plates 9 and 15 to rod 10 is reversed, ejector plate 15 being permanently secured to the rod and plate 9 attached to it by a lock nut. As will be apparent, this extinguisher is recharged by removing and inverting cap 3 and detaching plate 9, the plunger being pulled out to its fully extended position so as to draw the ejector plate to the inner end of the compartment and permit of its being refilled. As in the previous form the plunger may be locked in inactive position, the means here shown comprising a latch 21 pivoted on the gland nut 22 and arranged to enter a notch in the plunger rod 10.

Having now described my invention, I claim:

1. In a fire extinguisher, the combination of a liquid container, a powder compartment therein adapted to hold dry foam making ingredients normally out of contact with the liquid, and means for setting the extinguisher in action including an external operating handle, connections therefrom to the interior of the container and means associated therewith for coincidentally introducing the powder to and mixing the same with the liquid.

2. The combination in a fire extinguisher of a liquid container, a powder compartment therein arranged to hold the powder normally out of contact with the liquid, and means for setting the extinguisher in action including an external operating handle, connections therefrom to the interior of the container and positive ejector means for the powder associated therewith, said ejector means acting to transfer the powder from said compartment into the liquid and constituting an agitator therefor.

3. The combination as set forth in the preceding claim, in which said connections and ejector means comprise a plunger rod and a transverse plate member secured thereto, said rod being of sufficient length to permit movement of the plate into the liquid.

4. In a fire extinguisher, the combination of a liquid container, a movable powder supporting device arranged normally to hold dry ingredients out of contact with and sealed against vapors from the liquid, an external operating handle and connections therefrom to said device for agitating the same in and throughout the liquid, said container having a fixed outlet and attached nozzle for directing the discharge independently of the position of said handle.

5. In a fire extinguisher the combination of a liquid container, a powder compartment therein comprising a fixed side wall and top

and bottom walls movable relatively thereto, said compartment arranged to hold dry ingredients out of contact with the liquid, an external operating handle and means connecting said top and bottom walls with each other and with said handle, for the purpose described.

5 6. In a fire extinguisher of the kind described, the combination of a liquid container and a powder compartment, means for sealing the compartment, and means, including an external handle, operable to release said sealing means to discharge the powder into the liquid and coincidentally to agitate the

10 same.

7. In a fire extinguisher of the kind described, the combination of a liquid container, a closure cap therefor, a powder compartment having one end sealed by said cap, and

15 mixing means having an external operating handle, said means connected therewith inside the container and arranged to seal the other end of said compartment.

8. In a fire extinguisher having a liquid container and a powder compartment therein adapted to hold dry foam making ingredients normally out of contact with the liquid, a rod extending through the powder compartment and substantially throughout the length

20 of the liquid container, an external operating handle for reciprocating the rod and a mixer operated by said rod.

9. In a fire extinguisher, the combination set forth in claim 1 in which said connections

35 include an elongated rod normally positioned within the container and extending into the liquid and adapted to be reciprocated by said handle to set the extinguisher in action.

40 In testimony whereof, I have signed this specification.

WALTER R. ROLLO.
